(57) **CLAIM**

The ornamental design for an anti-slip sleeve for shoe, as shown and described.

DESCRIPTION

FIG. 1 is a perspective view of an anti-slip sleeve for shoe showing my new design;

FIG. 2 is a front view thereof;

FIG. 3 is a left side view thereof;

FIG. 4 is a right side view thereof;

FIG. 5 is a top plan view thereof; and,

FIG. 6 is a bottom plan view thereof.

In the drawings, the broken lines in FIGS. 1-6 depict portions of the design that form no part of the claim.
